UNITED STATES PATENT OFFICE.

WILLIAM E. MURBARGER, OF DAYTON, OHIO, ASSIGNOR OF ONE-HALF TO
THOMAS C. DOBBINS, OF SAME PLACE.

ANTI-RATTLER FOR THILL-COUPINGS.

SPECIFICATION forming part of Letters Patent No. 315,535, dated April 14, 1885.

Application filed August 7, 1884. (No model.)

To all whom it may concern:

Be it known that I, WILLIAM E. MURBARGER, a citizen of the United States, residing at Dayton, in the county of Montgomery and State of Ohio, have invented a certain new and useful Improvement in Anti-Rattlers for Thills; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to improvements in anti-rattlers for thills; and it consists of a steel plate bent upon itself, with ears extending down at the sides from the top end to embrace the ends of the coupling-pin. The other end 20 has a concavity on its face to partially embrace the eye of the thill-iron, and beneath said concavity is a clip to prevent the anti-rattler from becoming detached.

The mechanism is illustrated in the accompanying drawings, in which Figure I is a side view of a jack-clip with the anti-rattler attached. Fig. II is a front view of the anti-rattler.

At A is represented the ordinary form of 30 jack-clip for thills.

B is the thill-iron, which is connected to the clip by a pin or bolt.

The dotted lines at E, Figs. I and II, show 35 the position of the pin. The pin is cylindrical, and is only sufficiently long to extend the width of the jack-clip. The anti-rattler F is cut out of plate-steel and bent upon itself, as

shown at Fig. I, the top being cut wide to form the ears C, which are bent down so as to extend over the ears of the jack-clip, thereby 40 covering the ends of the pin. The other end is made concave on its front face to partially embrace the eye of the thill-iron, and beneath is cut out the clip D, which serves to prevent 45 the anti-rattler from being detached. The concave surface serves the same purpose, but is not so secure as the said clip.

The position of the anti-rattler in use is shown in Fig. I. It is introduced by entering the point between the ears of the jack-clip, and is forced down until the eye of the thill-iron enters the concavity, where it is 50 securely held by the resilience of the metal, and is further protected against being detached by the clip, as before specified. The ears of 55 the same hold the pin in position.

The same device may be used without the ears, and then a bolt must be substituted for the pin.

Having fully described my invention, what 60 I claim, and desire to secure by Letters Patent, is—

The anti-rattler F, with ears C to hold the coupling-pin, and clip D to retain the same in position in the jack-clip, substantially as set 65 forth.

In testimony that I claim the foregoing as my own I affix my signature in presence of two witnesses.

WILLIAM E. MURBARGER.
